Primary Examiner — Cathron C Brooks*Assistant Examiner* — Sharon S Oum(74) *Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing in the environment of a ceiling fan, showing my new design;

FIG. 2 is a bottom perspective view of the ceiling fan motor housing of FIG. 1;

FIG. 3 is a top view of the ceiling fan motor housing of FIG. 1;

FIG. 4 is a bottom view of the ceiling fan motor housing of FIG. 1; and,

FIG. 5 is a side view of the ceiling fan motor housing of FIG. 1.

Portions of the ceiling fan motor housing and ceiling fan environment shown in broken lines form no part of the claimed design.

1 Claim, 5 Drawing Sheets(56)
